US00D714557S

(12) **United States Design Patent**
Gonzalez et al.

(10) **Patent No.:** US D714,557 S
(45) **Date of Patent:** ** Oct. 7, 2014

(54) **U-BRUSH**

(71) Applicants: **Mario M. Gonzalez**, Kenosha, WI (US);
Noah Wangerin, Glenview, IL (US)

(72) Inventors: **Mario M. Gonzalez**, Kenosha, WI (US);
Noah Wangerin, Glenview, IL (US)

(73) Assignee: **Weber-Stephen Products LLC**,
Palatine, IL (US)

(**) Term: **14 Years**

(21) Appl. No.: **29/454,259**

(22) Filed: **May 8, 2013**

(51) **LOC (10) Cl.** 04-01

(52) **U.S. Cl.**

(57) **CLAIM**

The ornamental design for a U-brush, as shown and described in the following Figures.

DESCRIPTION

FIG. 1 is a perspective view of a U-brush of the present invention;

FIG. 2 is a top view of the brush of the present invention;

FIG. 3 is a right side view of the brush of the present invention, the left side being a mirror image thereof;

FIG. 4 is a bottom view of the brush of the present invention; and,

FIG. 6 is a rear view of the brush of the present invention. The broken lines illustrate portions of the article that form no part of the claimed design.

1 Claim, 2 Drawing Sheets
